(57) **CLAIM**

The ornamental design for the lopper, as shown and described.

DESCRIPTION

FIG. 1 is a right side view of the lopper.

FIG. 2 is a left side view of the lopper.

FIG. 3 is a front view of the lopper.

FIG. 4 is a back view of the lopper; and,

FIG. 5 is a right side perspective of the lopper.

The broken lines in the FIGS. 1-5 illustrate portions of the lopper which form no part of the claimed design.

1 Claim, 4 Drawing Sheets

FIG. 1

FIG. 2

FIG. 3**FIG. 4**

FIG. 5
